CLAIM

The ornamental design for an oriental chest, as shown and described.

DESCRIPTION

FIG. 1 is a top perspective view of an oriental chest showing our new design;

FIG. 2 is a left side elevational view as seen on display, the right side being a mirror image thereof;

FIG. 3 is a front elevational view thereof;

FIG. 4 is a rear elevational view thereof;

FIG. 5 is a front elevational view with the lid open;

FIG. 6 is a top plan view thereof; and

FIG. 7 is a perspective view thereof.
